CLAIM

The ornamental design for a urinary catheter assembly, as shown and described.

DESCRIPTION

FIG. 1 is a perspective view of a urinary catheter assembly (in position of use) showing our new design;

FIG. 2 is a rear elevational view of the urinary catheter assembly of FIG. 1;

FIG. 3 is a left side elevational view of the urinary catheter assembly of FIG. 1;

FIG. 4 is a front elevational view of the urinary catheter assembly of FIG. 1;

FIG. 5 is a right side elevational view of the urinary catheter assembly of FIG. 1;

FIG. 6 is a top plan view of the urinary catheter assembly of FIG. 1;

FIG. 7 is a bottom plan view of the urinary catheter assembly of FIG. 1; and,

FIG. 8 is another perspective view of the urinary catheter assembly showing our new design.

The broken lines in the figures show portions of the urinary catheter assembly that form no part of the claimed design.
